COMBINATION CANE AND RACK OR THE LIKE

Osborne C. Stanley, Winter Haven, Fla.

Application November 15, 1950, Serial No. 12,994

Term of patent 7 years

(Cl. D88—4)

To all whom it may concern:

Be it known that I, Osborne C. Stanley, a citizen of the United States of America, residing at Winter Haven, in the county of Polk and State of Florida, have invented a new, original, and ornamental Design for Combination Cane and Rack or the like, of which the following is a specification, reference being had to the accompanying drawing, forming part thereof.

In the drawing:

I claim:

The ornamental design for a combination cane and rack or the like, as shown.

OSBORNE C. STANLEY.
